UNITED STATES PATENT OFFICE.

AXEL W. CARLSON, OF WORCESTER, MASSACHUSETTS.

MEANS FOR MAKING TURBINE-ROTORS.

1,273,576.

Specification of Letters Patent. Patented July 23, 1918.

Original application filed February 23, 1918, Serial No. 218,860. Divided and this application filed April 20, 1918. Serial No. 229,729.

To all whom it may concern:

Be it known that I, AXEL W. CARLSON, a citizen of the United States, residing at Worcester, in the county of Worcester and 5 State of Massachusetts, have invented certain new and useful Improvements in Means for Making Turbine-Rotors, of which the following is a specification.

My present invention relates to a novel 10 device for use in the manufacture of rotors for elastic fluid turbine engines; the object being to provide a practically efficient means for facilitating the assembling of the turbine vanes, and for forming complete annular cores embracing the positioned vanes in 15 their assembled order, preparatory to casting the rotor-wheel upon the inner ends of the vanes.

A further object is to provide a circular 20 box with a removable clamping device adapted for the concentric temporary support of the entire circle of radially disposed vanes and a facing band, in their properly assembled relation, for application 25 thereto of an embedding annulus of core forming material.

These objects I attain by the means illustrated in the accompanying drawings, and more fully hereinafter explained.

30 Figure 1 of the drawings is a plan view with its quarterings shown at different levels; the upper quarter portion represents the core-box with its interior vacant; the portion at the left represents the annular core formed therein, and indicating the turbine buckets or vanes and face-band as assembled and incased in the annulus of core material. The portion at the right hand represents the structure of the lower clamp- 35 plate and section of the core-box at line X, or at the division level of the clamp devices; and the lower portion represents the top of the core-box with its cover on.

Fig. 2 represents a vertical central section 45 of the combined core-box and clamp-plates; one side showing the core as formed therein, the other side showing the core-forming space with the rotor vane supported therein ready for receiving the core material.

50 Fig. 3 represents the end and front of one of the buckets or vanes, drawn to larger scale; and Fig. 4 shows a side and cross-section detail of a portion of the perforated circular band employed for spacing the vanes 55 and forming the face of the rotor-wheel.

Referring to the drawings, numeral 2 indicates the buckets or vanes which are radially disposed about the periphery of the rotor. Said vanes, which are made of suitable composition metal, such as heretofore 60 employed for like purpose, are individually formed substantially as shown in Fig. 3, each having transverse offset shoulders 4 and a longitudinally projecting reduced 65 tongue or shank 5 at its inner end, preferably proportioned approximately as indicated, and provided with notches or grooves across the sides. The outer ends of the vanes may be provided with endwise projecting lugs 6.

70 Numeral 10 indicates an annular core-box, and 12 a circular clamp-plate adapted to be concentrically supported within the box 10, and retained in proper central relation by an offset or shoulder 11, against which the 75 lower corner of the plate fits; or by other efficient means. 13 indicates the upper plate of the clamp preferably formed as an annulus of equal diameter to the plate 12, and superposed thereon with its under surface 80 counter-matching the upper surface of the lower plate; their peripheral edges being uniform with each other and approximately upright, or slightly inclined from their junction line outward.

85 The adjacent faces of the clamp-plates 12 and 13 are provided near their periphery with a grip-space or radial recesses 15, adapted for receiving the tongues or shanks 5 of the vanes 2, and firmly clamping the 90 same in position when the two clamp-plates 12 and 13 are closed together; said plates having screws or bolts 16 arranged therein whereby the clamp can be conveniently tightened and released, as desired.

95 The removable flat annular cover 17 for the core-box is adapted for seating upon the top of the plate 13 and the top of the outer rim of the box, substantially as indicated.

100 The diameter of the clamp-plates 12 and 13 is made the same as the required diameter for the rotor-wheel casting, while the thickness of said plates together is such as to give the required depth of core-forming space.

105 The peripheral edges of the clamp-plates are adapted for supporting a complete circular band of metal 20, preferably a thin strip or ribbon of copper or steel about one-sixteenth inch, more or less, in thickness 110

and of a width equal to or slightly greater than the rim of the rotor-wheel. Said band is provided along its medial line with a series of perforations or holes 21 formed there-through, of a shape corresponding with the cross-section shape of the shanks 5 of the vanes, and spaced to correspond with the desired series spacing of the vanes about the circumference of the rotor. The relative 10 diameters of the plates and band are such that the circular band will fit closely, but removably, about the peripheral faces of the adjacent clamp-plates 12 and 13, with its openings 21 coincident with the clamp-spaces 15. The lower clamp plate is preferably formed with a central eye 3, so that the plates can be supported upon a suitable shaft or pindle while assembling the vanes in the clamping spaces 15.

20 In the manufacture of the turbine rotors, the band 20 is arranged around the clamp-plates when the latter are slightly separated, sufficient for insertion of the shanks 5 upon the inner ends of the vanes. All 25 the vanes are then assembled with their shanks 5 respectively inserted through the openings 21 in the band, into the space or spaces 15 between the clamp-plates, as at 23; the shoulders 4 resting against the exterior of the band, and the several vanes standing out radially at their respective spaced positions. The screws 16 are then turned down firmly clamping the shanks in 30 position and retaining the vanes in their proper relation. The clamp-plates are then placed within the circular-box 10, the parts being maintained concentric by the corner of the lower plate engaging with the shoulder 11 in the bottom of the box, the clamped 35 vanes projecting outward within the annular space 24, between the periphery of the clamp-plates and rim of the box 10. Said space is then filled with core material in- 40 casing the vanes 2 and exterior of the band 20 and forming a complete annular core 25 in which the vanes and band are retained at their required position. The top of said core is leveled off with the cover 17 of the box. A metal ring or hoop 18 of round or 45 flat wire may, when desired, be embedded in the material for reinforcing the core.

The clamp-plates 12 and 13, together with the formed core 25, are then removed from the box 10; the clamp screw 16 turned out

and the clamp-plates taken off, leaving the 55 band 20 retained in the core with the shanks 5 of the vanes 2 cleanly projecting inward from the inner face of the band, as best shown at 5 on Fig. 2. This circular core is baked to give it proper consistency about 60 the embedded vanes, and forms a complete cylindrical annulus, having the complete series of vanes and face band assembled therein in their proper relation, and in a form 65 which can be handled, stored or transported without deranging the circumferential adjustment of the vanes, and as a unitary circular element ready for its placement within the casting mold when producing the 70 rotor wheel.

I claim and desire to secure by Letters Patent—

1. In apparatus for the production of turbine rotors, the vane-supporting core-forming means, comprising a circular box, upper and lower clamp-plates concentrically supported therein and affording annular core space, said clamp-plates adapted for supporting a circumferential centrally perforated band, and the inner end shanks of 75 radially disposed vanes inserted therethrough, means for clamping said plates upon the shanks, said plates adapted for removal from the box together with a circular core formed in said core space, and having the projecting vanes and band embedded 80 therein.

2. In apparatus for the production of turbine rotors of the character described, a core-forming means comprising a circular box, a 90 circular clamp-plate adapted for concentric support within said box, an upper clamp-plate superposed thereon, said plates having countermatching surfaces adapted for clamp- 95 ing inwardly projecting shanks of rotor vanes, the peripheral edges of said clamp-plates adapted for supporting a circumferential band with central openings coincident with the shank clamping positions, adjusting screws connecting said plates, the 100 annular space between the periphery of the clamp-plates and rim of the box being greater than the length of the rotor vanes to be used.

Witness my hand this 18th day of April, 105
1918.

AXEL W. CARLSON.
